ELMER W. REBMAN, OF BUFFALO, NEW YORK, ASSIGNOR TO CONTRACTORS ORNAMENTAL STEEL CO. INC., OF BUFFALO, NEW YORK, A CORPORATION OF NEW YORK

METAL JOIST

Application filed October 17, 1929. Serial No. 400,326.

This invention relates to a metal joist construction.

The invention comprehends the provision of a metal joist having upper and lower chord members, tension members extending diagonally between these chord members and compression bars connecting the chord members and retaining the tension members in assembled relation therewith, in which the special construction of the tension members and the chord members provides for the use of reduced ends on the compression bars adapted to extend through registering openings in the tension and chord members so that the swaging of the reduced ends of the compression bars will rigidly assemble these parts together.

In the drawings:

Fig. 1 shows the joist member in perspective.

Fig. 2 is a sectional view taken on line 2-2 of Fig. 1.

Fig. 3 is a sectional view taken on line 3-3 of Fig. 2.

Fig. 4 is a sectional view taken on line 4-4 of Fig. 1.

Fig. 5 is a plan view showing the connections between the tension and compression members and the upper chord.

Fig. 6 is a perspective of an end of one of the compression rods.

The upper chord 1 consists of a straight channel bar having spaced openings 2 therein, said openings being elongated in one direction and having arcuate ends. The openings 2 are countersunk or chamfered at the upper side of the chord 1 as indicated at 3 in Fig. 3.

The lower chord 4 formed of a channel bar is spaced from the upper chord and is provided with a central portion 5 and end portions 6, offset from said central portion. The portions of bar joining the ends 6 with the central portion 5 are inclined as shown in Fig. 1. The lower chord 4 has a plurality of spaced openings aligned with openings 2 in the upper chord, and having countersunk portions at the lower face of the chord. The flanges on the upper and lower chords extend toward each other as shown in Fig. 1.

A plurality of tension bars are mounted between the central portion 5 of the lower chord and the opposite part of the upper chord. These bars include a central tension bar 7 having an intermediate foot portion 8 between the diagonal portions 9 while foot portions are provided at the ends of portions 9. The foot portion 8 is positioned against the inner face of the lower chord and has an opening in registry with one of the openings therein, while the end foot portions seat against the upper chord and have openings registering with the openings therein at opposite sides of the opening in alignment with the foot portion 8. Tension bars 11 provided with foot portions 12 on opposite ends extend between the upper and lower chords at opposite sides of portions 9 of bar 7 and are arranged in parallel relation thereto, the bars 11 at one side of bar 7 extending in one direction and the bars 11 at the other side of bar 7 extending in an angular direction but parallel to the adjacent portion 9. In each case the foot portions 12 are seated against the chords and have openings registering with openings in the chords.

Compression rods 13 extend between the upper and lower chords in substantially perpendicular relation and have reduced or recessed ends 14 extending through the registering openings in the foot portions of the tension bars and the chords. These ends 14 are swaged into the countersunk portions of the openings in the chords for rigidly assembling the chords, tension bars and compression rods. The rods 13 have shoulders 15 adjacent the reduced ends which engage the foot portions and cooperate to retain them against the chords when the reduced ends are swaged so that a rigid structure is obtained in which the tension bars and compression rods have stress distributing cooperation with the chords.

The opposite ends of chord 1 and the offset ends 6 of chord 4 are secured together by connecting plates 16. For this purpose plates 16 are provided with projections 17 extending through openings 18 in the chords and have their ends swaged into the countersunk portions to permanently secure the parts

together. The plates 16 are provided with openings 19 for use in mounting the joists in position for use.

From the foregoing description it will be seen that a joist construction is provided by this invention which comprises only three essential parts in which the compression rods perform a plurality of functions in securing an assembled structure which is rigid, economical to manufacture, and efficient in use.

10 What is claimed is:

1. An article of manufacture providing a metal joist, comprising a substantially straight elongated bar forming an upper chord member, a lower chord member formed of a bar having the ends offset relative to the central portion, connecting plates between the offset ends of the lower chord member and the ends of the upper chord member having the opposite edges secured to the bars forming said members, tension bars extending in diagonal relation between the central portions of the lower chord member and the upper chord member, each tension bar having angularly extending foot portions seated against said chord members and provided with openings in registry with openings in said chord members, compression rods having reduced extensions on opposite ends, said rods being mounted in substantially perpendicular relation between said chord members and having shoulders formed by said reduced ends seated against said foot portions, said reduced portions extending through said registering openings and having swaged terminals for permanently securing said rods, bars and chord members in assembled relation.

2. A metal joist comprising, an upper chord member, a lower chord member in spaced relation thereto, tension members having foot portions seated against said chord members and diagonally disposed portions extending between said chord members, the foot portions of said tension members being provided with openings in registry with openings in said chord members, and compression rods extending between said chord members in substantially perpendicular relation thereto, said rods having integral shoulders bearing on the foot portions of said tension members, having a substantially uniform section in the plane of said chords with end portions extending through the registering openings in said foot portions and chords, and provided with swaged terminals to completely fill said openings and permanently secure said rods, tension members and chord members in rigid assembled relation.
